UNITED STATES PATENT OFFICE.

FRANK E. MUNSELL, OF HAMILTON, MISSOURI.

SWITCH-KEY.

1,115,720.

Specification of Letters Patent.

Patented Nov. 3, 1914.

Application filed June 2, 1913. Serial No. 771,267.

To all whom it may concern:

Be it known that I, FRANK E. MUNSELL, a citizen of the United States, residing at Hamilton, in the county of Caldwell and State of Missouri, have invented certain new and useful Improvements in Switch-Keys, of which the following is a specification, reference being had to the accompanying drawing.

10 My invention relates to switch keys, and has for its objects, to provide a device readily removable from the table or mounting in which such keys are commonly used without unsoldering any connections, and which will be compact, durable, and cheap to manufacture.

15 In the accompanying figures, Figure 1 is a view, partly in section of a key embodying my invention. Fig. 2 an enlarged view of the plunger contact holder and plunger. Fig. 3 is a view of the contact spring used in the key.

20 The same figures of reference denote the same parts wherever they are shown.

25 The key table 1 supports the frame 2 carrying the block 3 of insulating material. A convenient form for the frame is that of a tube having a flange at the top: or it may be a stirrup-shaped piece. The exact form 30 is immaterial. In 3 are driven a number of plunger holders 4, one for each circuit connection to the key-switch. In each of these is placed a contact plunger 6, having a spring 7 attached to it, which has an end 8 35 adapted to be drawn through hole 9 in the holder and soldered, thereby forming a positive connection. Circuit wires 10 are soldered to the downwardly projecting ends of the holders 4. Any suitable form of key is 40 now mounted above the plungers, the springs of said key being so disposed or formed as to make contact with said plungers when the key is in position. Fig. 1

shows a well known form of key, provided with springs 11 having their lower extremities formed as shown at 12. When the escutcheon plate 13 carrying this key is clamped on frame 2 by bolts 14 and 15, or in any other manner, it is obvious that the key springs 11 will be in electrical connection with their respective circuit wires 10, through plungers 6 and their mounting tubes. And it is obvious that the key may be removed and replaced without the necessity of handling the wires 10, and that the contacts between 6 and 12 will always be correctly made, there being no possibility of reversing wires.

45 While I have shown but one form of construction it is obvious that my invention may be utilized in various ways without departing from the broad plan as herein disclosed of mounting a switch key above suitable touch-contact members thereby eliminating soldered or screw connections to the key proper. A modification from the form shown would be to omit the frame 2 and carry piece 3 and the parts it supports on the bottom of the usual key shelf, and support the key proper above it. All such 55 modifications I deem within the scope of my invention.

50 I claim—

55 In a switch key, a suitably supported frame, cylindrical plunger holders carried by said frame, resiliently actuated plungers mounted in said holders, an escutcheon removably secured to said frame, and a key carried by said escutcheon and adapted to contact said plungers.

60 In testimony whereof I hereunto affix my signature in the presence of two witnesses.

FRANK E. MUNSELL.
